UNITED STATES PATENT OFFICE.

EDWARD P. ALSTED, OF TRUESDELL, WISCONSIN.

ATTRITION-MILL GRINDING-DISK-FACING APPARATUS.

SPECIFICATION forming part of Letters Patent No. 783,406, dated February 28, 1905.

Application filed April 20, 1903. Serial No. 153,412.

To all whom it may concern:

Be it known that I, EDWARD P. ALSTED, residing at Truesdell, in the county of Kenosha and State of Wisconsin, have invented a new and useful Improvement in Attrition-Mill Grinding-Disk-Facing Apparatus, of which the following is a description, reference being had to the accompanying drawings, which are a part of this specification.

This invention relates to a portable apparatus for use of the mill operator for sharpening or regrinding the grinding-disks of attrition-mills.

Many of the attrition-mills now on the market are of the type in which the disk-cases are movable longitudinally of the bed, whereby access to the interior of the cases is obtained for repairing, for cleaning, for grinding the disk-faces, or for substituting new disks for those worn out or dulled.

As with the apparatus now on the market, with which I am familiar, it is practicably impossible to properly sharpen or to regrind the cutting-faces of the grinding-disks while in place. It is now customary instead of resharpening or grinding the disks as they become dulled to remove the same and replace them by new ones. The expense involved in replacing the dulled disks by new ones, including the cost of the disks and the labor, is considerable.

The object of this invention is to produce an apparatus by means of which the grinding-disks of attrition-mills may be properly sharpened or ground and resharpened or reground without removing said disks from the mill.

A further object of this invention is to produce an apparatus as above outlined which is in a nature portable—that is, an apparatus which may be moved from one mill to another and attached to the several mills for performing its function.

These and other objects I attain by means of the apparatus constructed as described in the specification and illustrated in the drawings presented herewith.

As the mill itself does not enter into this invention and as the grinding-disks of various types and makes of mills are adapted to be operated on by this apparatus, only a portion

of a mill is shown, said portion being considered sufficient to clearly illustrate the *modus operandi* of the apparatus and the means for attaching the apparatus to the mills.

In the drawings, Figure 1 is a plan view of this apparatus shown attached to the front and rear disk-cases of an attrition-mill, said mill being shown in a fragmentary manner. Fig. 2 is a view in side elevation of this apparatus. Figs. 3 and 4 are cross-sectional views of this apparatus and are taken on lines 3-3 and 4-4, respectively, in Fig. 2.

Throughout the several views like elements are denoted by like characters.

The apparatus preferably consists of a bed-plate or rod member 5, supported, by means of bolts 6, to yoke-irons 7, which in turn are supported on horizontal bolts or screws 8, which are threaded through ears 9 of supports 10, carried on opposite sides of the front and rear cases 11 and 12, respectively, of the mill, said cases, together with their grinding-disks, being moved away one from the other and longitudinally of the mill-bed to allow the grinding apparatus to be supported between them.

Journalized within boxes 13, carried by supports 14, a distance above bed 5 is a shaft 15, which is revoluble in said journal-boxes and movable longitudinally therein. A portion of said shaft 15, as at 16, is threaded, and mounted on the threaded portion is a grinding or abrading wheel 17, preferably of emery or similar material. Double lock-nuts, as shown in the drawings, are threaded onto said shaft 15, two on either side of said abrading-wheel, whereby said wheel will be locked against rotation, except with said shaft 15; as said shaft rotates in either direction.

The outer end of shaft 15 carries a belt-wheel or pulley 18, provided with a wide belt-face, as shown in Figs. 1 and 2, whereby said wheel may be moved longitudinally with the shaft and still be driven by the belt which passes over it.

A screw-shaft 19, passing loosely through one of the supports 14, is journaled at its outer end within a bearing member 20, carried by bed 5. Said shaft at its outer end is provided with a hand-wheel 21, whereby the same may

be rotated. The inner or threaded end of shaft 19 passes through a threaded eye in a yoked member 22, which is supported and guided on bed 5 by means of a guiding member 23, the 5 opposite ends of which project downwardly and lie on opposite sides of bed 5. Each of the arms of the yoke 22 loosely surrounds shaft 15, and inside of each arm stops 24, in the nature of set-collars, are secured to shaft 10 15. It will be seen from this construction that as screw-rod 19 is rotated, shaft 15 will be moved longitudinally within its journals 13. Bolts 6, which secure the bed to the yokes 7, pass through slotted openings 25, and in 15 order to adjust the abrading-wheel into contact with the grinding-disks 26 of the mill adjustment-screws 27 are provided. These screws are threaded through depending ears of the yokes 7, and by means of them the bed 20 20 5 may be moved to and held in the desired positions. By means of screws 8, which are locked in adjusted position by means of lock-nuts located on either side of ears 9, the shaft 15 and the abrading-wheel are adjustable laterally.

While the shaft 15 may be driven from any suitable power source, it has been found desirable to drive the same from the main shaft 28 of the mill, and as the two shafts 15 and 30 30 28 stand at right angles one to the other it is necessary to provide idler directing-pulleys for the belt 29, by which the pulley 18 is driven from a pulley 30, carried by shaft 28. These idler-pulleys are numbered 31 and 32, respectively, and are loosely mounted on a vertical shaft carried by a supporting-bracket 33, which is preferably bolted to bed 5. The bracket 33 is provided with slots 34 for accomplishing the desired tension of belt 29.

40 After one of the grinding-disks of the mill has been refaced or sharpened the bed 5 may be adjusted to bring the abrading-wheel into proper contact with the other grinding-disk, whereby it may be refaced.

45 From the arrangement shown in the drawings it will be seen that the abrading-wheel and the grinding-disks of the mill will be driven in opposite directions when the grinding-disks are being refaced, and while thus being driven the abrading-wheel may be moved across the face of the disk to be reground at the desired rate of speed by the hand-wheel and screw-rod. By inclining the bed 5 off of 50 parallel from the grinding-faces of the grinding-disks it will be possible to reface the grinding-disks so that they are partially concave or convex, as is desired.

It will be understood that while the drawings presented herewith illustrate a practical 60 embodiment of this invention the invention is not limited to the exact construction shown. Various changes may be made in the apparatus for accommodating it to mills of various types and makes without departing from the 65 spirit of this invention.

The bed member 5 is provided with a longitudinally-extending slot 35, (shown by dotted lines in Fig. 2,) and by means of this slot the bolt 25, which passes through the same, may be moved longitudinally of the bed to 70 accommodate mill-cases of varying diameters.

Having thus described my invention, I claim—

1. In an attrition-mill grinding-disk-facing apparatus, a pair of yokes adapted to connect the separated disk-cases of an attrition-mill on opposite sides thereof, a rod or bed-plate 75 adjustably supported by the yokes between the grinding-disks, and a rotatable abrading-wheel mounted on the rod or bed-plate and adjustable thereon across the face of one of the grinding-disks.

2. In an attrition-mill grinding-disk-facing apparatus, a pair of yokes adapted to connect the separated disk-cases of an attrition-mill 85 on opposite sides thereof, a rod or bed-plate slidably supported by the yokes, means for adjusting the rod or bed-plate with relation to either of the grinding-disks, and a rotatable abrading-wheel mounted on the rod or bed-plate.

3. In an attrition-mill grinding-disk-facing apparatus, a supporting member, means for clamping said supporting member to the separated disk-cases of an attrition-mill on opposite sides thereof, means for adjusting said supporting member toward or away from one or the other of the grinding-disks of the attrition-mill, a revolute abrading member 95 mounted on said supporting member and movable toward and away from the axis of rotation of said grinding-disks, and means for rotating said abrading member.

4. In a device of the character described, yokes capable of being clamped to the opposite sides of the opened disk-cases of an attrition-mill, a rod or bed-plate slidably supported by the yokes, adjusting-screws threaded in the yokes and bearing on opposite sides of the rod or bed-plate whereby the said rod or bed-plate may be adjusted toward either of the attrition-disks, a rotatable abrading-wheel mounted on the rod or bed-plate, and means for adjusting the abrading-wheel across the 100 face of either of the attrition-disks.

5. In a device of the character described, yokes capable of being clamped to the opposite sides of the opened disk-cases of an attrition-mill, a rod or bed-plate slidably supported by the yokes and adjustable toward either 110 of the attrition-disks, a shaft slidably journaled on the rod or bed-plate, an abrading-wheel mounted on the shaft, and means for rotating and sliding the shaft.

6. In a device of the character described, 115 yokes capable of being clamped to opposite sides of the opened disk-cases of an attrition-mill, a rod or bed-plate slidably supported by the yokes and adjustable toward either of the attrition-disks, a shaft slidably journaled on 120

the rod or bed-plate, an abrading-wheel carried by the shaft, a feed-screw mounted on the rod or bed-plate, and means connecting the shaft with the feed-screw whereby the abrading-wheel may be adjusted across the face of either of the attrition-disks.

7. In a device of the character described, a bed-plate, means thereon for connecting with opposite sides of opened disk-cases of an attrition-mill, supports on the bed-plate, a shaft slidably journaled in the supports, an abrading-wheel carried by the shaft, means for rotating the shaft, and means for moving the shaft longitudinally to cause the abrading-wheel to travel over the face of one of the grinding-disks of the attrition-mill.

8. In a device of the character described, a rod or bed-plate, means for securing the rod or bed-plate to opposite sides of the opened disk-cases of an attrition-mill, supports mounted on the rod or bed-plate, a shaft slidably journaled in the supports, an abrading-wheel carried by the shaft, means for rotating the shaft, a member having connection with the shaft but locked against independent longitudinal movement thereon, and a feed-screw supported from the rod or bed-plate and threaded in the said member and adapted to cause the abrading-wheel to travel over the face of one of the grinding-disks of the attrition-mill.

9. In a device of the character described, a rod or bed-plate, means for securing the rod or bed-plate to opposite sides of the opened disk-cases of an attrition-mill, supports mounted on the rod or bed-plate, a shaft slidably journaled in the supports, an abrading-wheel carried by the shaft, means for rotating the shaft,

a yoke member having loose connection with the shaft, stops on the shaft to prevent longitudinal movement of the yoke thereon, said yoke having a sliding connection with the rod or bed-plate, and a feed-screw mounted in a bearing on the rod or bed-plate and threaded in one of the arms of the yoke.

10. In a device of the character described, a rod or bed-plate, means for securing the rod or bed-plate to opposite sides of the opened disk-cases of an attrition-mill, supports mounted on the rod or bed-plate, a shaft slidably journaled in the supports, an abrading-wheel carried by the shaft, means for moving the shaft longitudinally, an elongated pulley on the shaft, and a belt driven from the shaft of the attrition-mill and passing around the elongated pulley.

11. In a device of the character described, a rod or bed-plate, means for securing the rod or bed-plate to opposite sides of the opened disk-cases of an attrition-mill, supports mounted on the rod or bed-plate, a shaft slidably journaled in the supports, an abrading-wheel carried by the shaft, means for moving the shaft longitudinally, an elongated pulley on the shaft, an adjustable bracket supported by the rod or bed-plate, idler-pulleys carried thereby, and a belt driven from the shaft of the attrition-mill and passing over the idler-pulleys and around the elongated pulley.

In testimony whereof I affix my signature in presence of two witnesses.

EDWARD P. ALSTED.
